CROWN BLOCK

Erwin Burns, Los Angeles, and Harry P. Wicker-
sham, Huntington Park, Calif.

Application January 7, 1935, Serial No. 665

11 Claims. (Cl. 254—190)

This invention relates to crown blocks and relates more particularly to crown blocks for use on the derricks of oil wells, gas wells, etc. A general object of the invention is to provide a compact, improved and simplified crown block.

The crown blocks that are used on the derricks of oil wells and gas wells usually include, in addition to the shaft and sheaves, a large number of sections or parts such as mounting members, 10 end plates, spacers, rods, etc. Such sectional crown blocks are large and cumbersome and are very expensive to manufacture and assemble.

Another object of the invention is to provide a crown block that embodies a minimum number 15 of parts and that is simple and inexpensive of manufacture.

Another object of the invention is to provide a crown block embodying a single integral or one piece body structure carrying the sheave supporting axle or shaft.

Another object of the invention is to provide a crown block including an integral or unitary body having partitions or spacers formed thereon for spacing the sheaves.

Another object of the invention is to provide a crown block of the character mentioned in which the integral spacers of the unitary body cooperate with or fit in grooves in the sheave supporting shaft to reinforce and brace the structure.

Another object of the invention is to provide a crown block that embodies a novel and improved cover which shields and protects the upper portions of the sheaves and prevents the cables or lines from escaping from the sheaves.

A further object of the invention is to provide a crown block of the character mentioned in which the sheave protecting hood or cover retains the shaft in the bearings of the body.

The various objects and features of our invention will be fully understood from the following detailed description of a typical preferred form and application of our invention, throughout which description reference is made to the accompanying drawings, in which:

Fig. 1 is an end elevation of the crown block provided by this invention with a portion broken away to illustrate one of the sides of the body in vertical cross section. Fig. 2 is an enlarged vertical detailed sectional view taken as indicated by line 2—2 on Fig. 1 and Fig. 3 is a horizontal detailed sectional view taken substantially as indicated by line 3—3 on Fig. 2.

The improved crown block of our invention includes, generally, a body 10, an axle or shaft 11 on the body 10, sheaves 12 carried by the shaft

11, and a hood or cover 13 on the body extending over the upper portions of the sheaves.

The body 10 is adapted to be mounted or arranged on the head or water tower of a well derrick. The formation or construction of the body 10 is an important feature of the invention, it being particularly significant that the body 10 is a single, integral or one piece member. In practice the integral body 10 may be formed of cast iron. The body 10 comprises or includes two 10 spaced end plates 14 and two spaced side walls or sides 15. The end plates 14 and the sides 15 are preferably vertical and the end plates 14 are preferably normal to or at right angles to the sides 15. A base web or bottom wall 16 extends horizontally between and integrally joins the end plates 14 and the sides 15 so that the body 10 is a box-like structure having an open upper end for the reception of the shaft 11 and the sheaves 12.

Mounting wings 17 extend outwardly from the opposite ends of the end plates 14. The wings 17 may be simple, integral continuations or portions of the end plates 14 and may lie in the same vertical planes as the end plates. The wings 17 25 are adapted to mount or support the crown block body 10 on the beams or supports of the water tower on the upper end of the derrick. Outwardly or laterally projecting flanges 18 extend along the lower ends of the wings 17 to rest on the supports of the derrick or water tower. The lower support engaging surfaces of the flanges 18 are preferably in a horizontal plane below the plane of the bottom wall 16 and other portions of the body 10. The flanges 18 of the wings 30 20 provide a simple effective means for securing the crown block in position. The upper ends of the wings 17 and the major portions of the upper ends of the end plates 14 preferably slope upwardly and inwardly, as clearly illustrated in 35 Fig. 1 of the drawings. Outwardly projecting strengthening or reinforcing flanges 19 extend along the upper and lower edges of the sides 15, the upper and lower edges of the end plates 14 and continue along the tops and opposite ends 40 of the wings 17. Similar reinforcing ribs or flanges 20 may be provided on the outer surfaces of the end plates 14 where the end plates and wings 17 join. The end plates 14, the wings 17 and the other wall parts of the body 10 may be 45 perforated or provided with openings to lighten the body structure, if found necessary or desirable.

In accordance with the invention partitions or spacers 21 are provided in the body 10 to ex- 55

tend between and space the several sheaves 12. The spacers are spaced vertically disposed parts and project upwardly from the bottom wall 16. The spacers 21 preferably extend between the 5 opposite sides 15 and integrally join the sides and the bottom wall 16. In the particular form of the invention illustrated in the drawings there are four equally spaced partitions or spacers 21 dividing the interior of the body 10 into five 10 like or equal compartments 22 for receiving a like number of sheaves 12. It is to be understood that the sides 15, the bottom wall 16, the end plates 14, the wings 17, the flanges thereof, and the spacers 21, are integrally joined or connected parts of a single one piece member or casting constituting the body 10 of the crown block.

The sheave supporting axle or shaft 11 is carried by the body 10 and is retained thereon by 20 bearing cap parts of the unitary hood or cover 13 as will be hereinafter described. The shaft 11 extends transversely or horizontally across the upper end of the body 10 between the end plates 14 to support the plurality of sheaves 12. 25 Outwardly projecting bearing bosses 23 are formed or provided on the upper ends of the end plates 14. The bearing bosses 23 are provided with suitable substantially semi-circular openings or seats 24 for receiving the opposite 30 end portions 25 of the shaft 11. The present invention provides a plurality of enlarged cylindrical bearing portions 26 on the shaft for supporting the sheaves 12 for rotation in spaced vertical planes. The bearing portions 26 of the 35 shaft 11 are spaced apart to provide or leave a plurality of longitudinally spaced annular grooves 27. The body partitions or spacers 21 cooperate with or extend into the grooves 27 of the shaft 11. Enlarged or thickened portions 40 28 are provided on the upper ends of the spacers 21 to extend into the grooves 27. The opposite side surfaces of the portions 28 are flat and parallel, and concave or semi-circular seats 29 are provided in the upper ends of the portions 45 28 so that the portions properly fit in or cooperate with the grooves 27. The grooves 27 and spacer portions 28 cooperating as just described effectively brace and reinforce the structure and the spacers constitute longitudinally spaced supports for the shaft 11. The outer ends of the 50 outermost bearing portions 26 of the shaft 11 may engage or cooperate with the inner surfaces of the end plates 14 as at 30.

The sheaves 12 are provided to carry the cables 55 or lines employed in drilling and operating the well. A sheave 12 is independently rotatable on each bearing portion 26 of the shaft 11. Suitable anti-friction bearings 31 rotatably support or mount the sheaves 12 on the bearing portions 26. The several sheaves 12 may be alike in form 60 and of the same effective diameter as illustrated throughout the drawings. The sheaves 12 may comprise thickened hubs 32, bodies or webs 33 and rims 34. The rims 34 have grooves 65 35 for receiving or carrying the lines. The particular sheaves illustrated in the drawings have outwardly flaring line carrying grooves 35. Openings 36 are provided in the lower body wall 16 for freely passing the lines that operate over the 70 sheaves 12. The sheaves 12 have suitable operating clearance with the body spacers 21 and the end plates 14.

The hood or cover 13 is arranged on the body 75 10 to extend over and shield the sheaves 12. The cover 13 is removable from the body 10 to

make the sheaves 12 accessible. In accordance with the invention the hood or cover 13 is a simple, integral member comprising a top or outer wall 36 and ends 37. The outer wall 36 of the cover is substantially cylindrically curved 5 about the longitudinal axis of the shaft 11 to extend around or over the rims of the sheaves 12 with substantial clearance. The ends 37 extend downwardly from the outer wall 36 to the body 10. Outwardly projecting flanges 38 10 extend along the lower ends of the outer wall 36 to seat on corresponding or opposing flanges 39 on the sides 15 of the body. Screws or bolts 40 may removably connect the flanges 38 with the flanges 39 to attach the cover 13 to the body. 15 The cover 13 mounted on the body in this manner may be removed when desired. The ends 37 of the cover may extend downwardly to the inclined upper ends of the body end plates 14. If found desirable openings 41 may be provided 20 in the opposite ends 37 of the cover to lighten its weight.

In the preferred form of the invention the hood or cover 13 operates to retain the shaft 11 assembled on the body 10. The ends 37 of the 25 cover have outwardly projecting bearing caps 42. The bearing caps 42 are integral with the cover 13 and are complementary to or oppose the bearing bosses 23 of the body. Integral lugs or ears 43 are provided on the bearing caps 42 to 30 seat on ears 44 of the bearing bosses 23. Bolts or screws 45 may connect the ears 43 and 44. The pairs of bearing bosses 23 and bearing caps 42 of the unitary body 10 and one piece cover 13 effectively and dependably retain or mount the sheave 35 carrying shaft 11. The top or outer wall 36 of the cover 13 is provided on its inner side with fins or flanges 46. The flanges 46 project downwardly or inwardly and are in vertical alignment with the spacers 21. The flanges 46 project 40 downwardly between the rims 34 of the sheaves 12 to positively prevent the escape of the lines from the sheaves and to prevent the lines from passing between or from becoming caught between the spaced adjacent sheaves. 45

It is believed that the utility and practicability of the crown block of my invention will be apparent from the foregoing detailed description. The crown block embodies a minimum number of parts, comprising only three principal parts 50 or units, namely the unitary body 10, the assembly of the shaft 11 and the sheaves 12, and the integral cover 13. The body 10 instead of being fabricated of numerous plates, beams, rods, etc. is a single integral casting. Accordingly, the 55 crown block body of the present invention is much simpler and more inexpensive than the bodies of the crown blocks heretofore introduced. The sheave carrying shaft 11 is dependably supported on the integral end plates 14 of the body 60 and the spacers 21 of the body in addition to spacing the sheaves 12 support and brace the assembly of the shaft and sheaves. The wings 17 with their supporting flanges 18 constitute a single, practical means for mounting the crown 65 block and for facilitating its attachment to its mounts or supports. The hood or cover 13 fully shields the upper portions of the sheaves 12 and its ends 37 and flanges 46 prevent the lines from escaping from the sheaves. The bearing caps 70 42 integrally formed on the cover 13 operate to retain the shaft 11 in the bearing openings 24. The simple one piece cover 13 may be easily detached from the body 10 to render the sheaves 75 and lines accessible. The crown block of the 75

present invention is particularly inexpensive of manufacture and is easily assembled.

Having described only a typical preferred form and application of our invention, we do not wish 5 to be limited or restricted to the specific form and application herein set forth, but wish to reserve to ourselves any modifications or variations that may appear to those skilled in the art or fall within the scope of the following claims.

10 Having described our invention, we claim:

1. A crown block including an integral body, a shaft carried by the body, and a multiplicity of sheaves on the shaft, the body including spacers between the sheaves.

15 2. A crown block including a body of box-form, a shaft extending between and supported on spaced ends of the body, sheaves on the shaft, and a cover on the body extending over the sheaves.

20 3. A crown block including a body of box-form, a shaft extending between and supported on spaced ends of the body, sheaves on the shaft, and spacers extending between the other ends of the body and projecting between the sheaves.

25 4. A crown block including a unitary body of box-form, a shaft extending between and supported on spaced ends of the body, sheaves on the shaft, and spacers on the bottom of the body projecting between the sheaves.

30 5. A crown block including a body, a shaft carried by the body and having spaced grooves, sheaves on the portions of the shaft between the grooves, and spacers on the body projecting between the sheaves and cooperating with the grooves.

35 6. A crown block including a body having spaced ends, a shaft supported on said ends, sheaves on the shaft, a bottom wall extending between and connected with the ends, and spacers

on the bottom wall projecting upwardly between the sheaves.

7. A crown block including a unitary body comprising spaced ends, a wall part extending between and connecting the ends, and spaced vertical spacers connected with said wall part, a shaft supported on the ends, sheaves on the shaft spaced to have the spacers enter between them, a cover on the body extending over the sheaves, and parts on the cover projecting inwardly between the sheaves. 10

8. A crown block including a unitary body comprising spaced ends, a wall part extending between and connecting the ends, and spaced vertical spacers connected with said wall part, a shaft 15 supported on the ends and having longitudinally spaced grooves receiving the upper portions of the spacers, and sheaves on the shaft between said grooves.

9. In a crown block, an integral body comprising a bottom wall, spaced sides projecting from the bottom wall, spaced ends projecting from the bottom wall and adapted to carry a shaft, and spacers extending between said sides and projecting upwardly from the bottom wall to project 25 between sheaves on said shaft.

10. A crown block including a body having bearing parts, a shaft supported by the parts, sheaves on the shaft, and a cover on the body retaining the shaft on the bearing parts. 30

11. A crown block including a body having bearing parts, a shaft supported by the parts, sheaves on the shaft, a cover on the body extending over the sheaves and adapted to retain the shaft on the bearing parts, and means removably 35 securing the cover to the body.

ERWIN BURNS.
HARRY P. WICKERSHAM.
